UNITED STATES PATENT OFFICE.

GEORGE L. FULLER, OF MIAMI, FLORIDA.

DOOR HOLDER.

Application filed July 3, 1928. Serial No. 290,168.

This invention relates to a door holder by which an open door may be rigidly held in place so that it cannot move in either direction; and the invention has for its object to provide a door holder which is simple in construction, so that it may be manufactured at little cost, and which is efficient in operation. To this end the improved door holder, as preferably constructed, consists of only three main sheet metal parts, two pivot pins and a single coil spring, all of which will be hereinafter more fully set forth.

In the accompanying drawing Fig. 1 is a side view of the improved door holder in operative relation to a door, and Fig. 2 is a similar view with the holding leg or brace in release position. Fig. 3 is a front view of the holder with the parts in the position shown in Fig. 1. Fig. 4 is a view similar to Fig. 3 but with the holding leg or brace broken away. Fig. 5 is a detail section on line 5—5, Fig. 1. Fig. 6 is a broken-out view showing the holding leg or brace in locked position.

Referring to the drawing, 12 denotes a bracket the back of which is provided with holes for screws 13, by which said bracket may be attached to a door A. Extending forward from the back part 12 of the bracket are two side flanges 12^a so that the said bracket is of U-shape in cross section. Attached to the flanges 12^a of the bracket, by a pivot pin 14, is a brace or leg 15 having an enlarged foot portion 15^a to the lower end of which is fixedly attached a pad or foot 16 of rubber or other suitable friction material. The leg or brace 15 is also preferably of U-shape in cross section, as shown in Fig. 5.

Between the top of the leg or brace 15 and the back of the bracket 12 is arranged a vertically movable dogging wedge member 17 which is also preferably of U-shape in cross section and to which an operating lever 18 is attached by a pivot pin 19. The wedge member 17 contacts with the upper part of the leg or brace 15 when in lowered position to hold said leg or brace in operative position shown in Figs. 1, 3 and 6. Connected with the pivot pin 19, at the inner part of the operating lever 18, and a struck-out hook 12^b on the bracket 12, is a spiral spring 20. The sliding wedge 17 is normally drawn downward by said spring so as to hold its inclined edges in contact with the upper part of the leg or brace 15 to dog the latter. The inner part of the operating lever 18, through which the pivot pin 19 passes, is preferably

of U-shape in cross section, the outer part of said lever being preferably somewhat flattened to afford a finger piece 18^a.

In the operation of the improved holder, when the parts are in the positions shown in Figs. 1, 3 and 6, the sliding wedge 17 will be held against the upper part of the U-shaped leg or brace 15, and the said leg or brace will thus be rigidly dogged in position so as to hold a door firmly in place in such a manner that it cannot move in either direction. When, however, the operating lever 18 is turned downward to the position shown in Fig. 2 the wedge 17 will be lifted, thus releasing the leg or brace 15 which will then be free to be moved to either of the positions shown in full or dotted lines in Fig. 2, thereby releasing the door A.

The wedge 17 is preferably held in sliding relation to the side flanges 12^a of the bracket 12 by constructing said flanges with hollow struck-out vertical ribs 12^c in which the ends of the pin 19 work.

From the foregoing it will be understood that the invention provides a door holder of simple construction in that it is preferably composed of three principal sheet metal parts, aside from the two pivot pins and spring hereinbefore referred to, and thus the holder may be manufactured at little expense by stamping, no milling being required in its construction.

The invention is, however, not to be understood as being limited to the details herein shown and described as the spring-drawn, sliding wedge and the co-operating holding leg or brace might be of solid metal without departing from the principle of the invention as defined by the claims hereunto appended.

Having thus described my invention I claim and desire to secure by Letters Patent:

1. A door holder comprising an attaching bracket, a holding brace pivotally connected with said bracket and having a friction foot, a vertically movable wedge member interposed between said bracket and the upper part of said brace, an operating lever pivotally connected with the upper part of said wedge member and a spiral spring connecting the inner part of said operating lever with the lower part of said bracket.

2. A door holder comprising an attaching bracket, a holding brace pivotally connected with said bracket and having a friction foot, a vertically movable wedge member interposed between said bracket and the upper part

of said brace, an operating lever pivotally connected with the upper part of said wedge member, and a spiral spring connecting the inner part of said operating lever with the lower part of said bracket, the pivot connecting said operating lever and said wedge being inside of the vertical plane of the pivot connecting said brace and said bracket.

3. A door holder comprising an attaching bracket, having forwardly extending side flanges, a holding brace pivotally connected with said bracket and having a friction foot, a wedge member movably mounted between said side flanges of said bracket and the upper part of said brace, an operating lever pivotally connected with the upper part of said wedge member, and a spiral spring connecting the inner part of said operating lever

with the lower part of said bracket, the pivot connecting said operating lever and said wedge being inside the vertical plane of the pivot connecting said brace and said bracket.

4. A door holder comprising an attaching bracket, a holding brace pivotally connected with said bracket, a wedge member interposed between said bracket and the upper part of said brace, an operating lever pivotally connected with the upper part of said wedge member, and a spiral spring connecting the inner part of said operating lever with the lower part of said bracket; said bracket, wedge member and the inner part of said operating lever being all of sheet metal and of U-shaped construction in cross section.

In testimony whereof I affix my signature.
GEORGE L. FULLER.
